United States Patent

Des. 240,822

Patented Aug. 3, 1976

240,822

CARTRIDGE CASE

Thomas G. Burke, 6231 182nd St. SW.,
Lynnwood, Wash. 98036

Filed Nov. 27, 1974, Ser. No. 527,564

Term of patent 14 years

Int. Cl. D3—02

U.S. Cl. D22—14

FIG. 1

FIG. 2

FIG. 1 is a front perspective view of a cartridge case, with the flap open showing the interior pockets embodying my new design.

FIG. 2 is a rear perspective view as viewed with the flaps closed.

I claim:

The ornamental design for a cartridge case, substantially as shown.
